PICTURE EXHIBITOR.
APPLICATION FILED MAR. 30, 1907.

2 SHEETS—SHEET 2.

UNITED STATES PATENT OFFICE.

ERNST CARL GUSTAV ROESLER, OF PHILADELPHIA, PENNSYLVANIA.

PICTURE-EXHIBITOR.

No. 872,455.

Specification of Letters Patent.

Patented Dec. 3, 1907.

Application filed March 30, 1907. Serial No. 365,500.

To all whom it may concern:

Be it known that I, ERNST CARL GUSTAV ROESLER, a citizen of the United States, residing at Philadelphia, in the county of 5 Philadelphia and State of Pennsylvania, have invented a new and useful Picture-Exhibitor, of which the following is a specification.

This invention relates to picture exhibitors 10 of that general class especially designed for displaying photographs, stereoscopic views and the like and has for its object to provide means whereby the photographs may be successively displayed without the necessity 15 of manually handling the same or without exposing the pictures in any manner.

A further object of the invention is to provide a case or housing having a plurality of 20 superposed compartments for the reception 20 of the photographs or pictures to be exhibited, said case or housing being provided with display openings to permit inspection of the pictures.

A further object is to provide means for 25 successively transferring the pictures from one compartment to the other, and means for locking the pictures in the upper compartment against accidental displacement during the ascent of the pictures from the 30 lower compartment.

A further object is to provide an actuating member having a lifting device pivotally mounted thereon and adapted to successively engage the pictures in the lower compartment and transfer the same to the upper 35 compartment.

A further object is to provide means for discharging one of the pictures from the upper compartment into the lower compartment 40 at each operation of the actuating member, and means for yieldably supporting the actuating member in inoperative position.

A still further object of the invention is to 45 generally improve this class of devices so as to increase their utility, durability and efficiency.

Further objects and advantages will appear in the following description, it being understood that various changes in form, 50 proportions and minor details of construction may be resorted to within the scope of the appended claims.

In the accompanying drawings forming a part of this specification: Figure 1 is a per-

spective view partly in section of a picture 55 exhibitor constructed in accordance with my invention. Fig. 2 is a longitudinal sectional view of the same. Fig. 3 is a vertical sectional view taken on the line 3—3 of Fig. 2 and showing the several parts in inoperative 60 position. Fig. 4 is a similar view showing the manner of transferring one of the pictures from the lower compartment to the upper compartment. Fig. 5 is a detail transverse sectional view of the lifting member. 65

Similar numerals of reference indicate corresponding parts in all of the figures of the drawings.

The improved exhibitor forming the subject matter of the present invention includes 70 a case or housing 5 preferably rectangular in shape, as shown and provided with a plurality of display openings 6 through which the photographs, pictures or other matter within the case may be readily inspected. 75

The interior of the case 5 is divided by a transverse partition 7 to form superposed compartments 8 and 9 adapted to receive or contain a plurality of frames 10 in which are mounted the photographs or pictures to be 80 exhibited.

Spaced laterally from the back of the case are parallel bars or guides 12 defining a rear chamber or compartment 13 and extending longitudinally within the compartment 13 85 are spaced rods 14 having their opposite ends secured to anchoring plates 15, which latter bear against the top and bottom of the case or housing 5, as shown. Slidably mounted on the rods 14 is an actuating device 16 preferably in the form of a tubular member or sleeve 17 the upper end of which is provided with a laterally extending finger piece 18 which projects through a slot 18' extending vertically of the case or housing. The sleeve 17 is 95 rigidly secured to a plate 19 having spaced perforations formed therein for the reception of the rods 14 and extending laterally from the plate 19 is a horizontally disposed arm 20 carrying a lifting device 21. 100

The lifting device 21 consists of a flat plate having its inner end coiled around and pivotally connected to the adjacent end of the arm 20 so as to permit free tilting movement of the lifting device on said arm. The lifting device 21 is normally and yieldably supported in elevated or inoperative position by means of a coiled spring 22 one end of which

is secured to the adjacent anchoring plate 15 while the opposite end thereof is secured in any suitable manner to the plate 19. It will thus be seen that when the finger piece 18 is 5 depressed the pivoted lifting device 21 will move downwardly within the rear compartment 13 and engage the lower end of the adjacent frame 10 so that when the finger piece 10 is released said frame will be transferred from the lower compartment 9 to the upper compartment 8.

Attention is here called to the fact that the rearward or tilting movement of the lifting device 21 is limited by engagement with the 15 shoulder 22' whereby when the finger piece 18 is depressed the lifting device will assume a substantially vertical position but will return to horizontal position and support the adjacent frame when the actuating device is 20 released.

As a means for locking the frames 10 in the upper compartment 8 during the ascent of the pictures from the lower compartment suitable locking devices 23 are provided, said 25 locking devices being slidably mounted on the upper face of the partition 7 at the opposite sides of the case 5, as shown.

The locking devices 23 are preferably in the form of flat plates provided with depending 30 perforated lugs 24 for the reception of the pins or rods 25, the latter being seated in suitable recesses 26 formed in the upper face of the transverse partition 7 beneath the locking devices, as shown. The rear ends of 35 the locking members or plates 23 are normally and yieldably supported in engagement with the adjacent guide bars 12 by means of the coiled springs 27 which bear against the lugs 24 and the adjacent walls of 40 the recesses 26, as best illustrated in Fig. 3 of the drawing. It will thus be seen that the locking devices 23 serve to normally cut off communication between the upper and lower compartments 8 and 9, respectively at the 45 rear of the case and thus prevent the pictures in the upper compartment from dropping into the lower compartment.

Extending transversely across the opposite ends of the partition 7 and secured in any 50 suitable manner to the lower face thereof are reinforcing plates 28 on which are pivotally mounted for lateral movement shoes or flaps 29. The free ends of the flaps or shoes 29 extend vertically beyond the upper surface 55 of the locking members 23 and bear against the adjacent picture frame 10 in the upper compartment so that when one of the pictures from the lower compartment is transferred to the upper compartment said pictures 60 will bear against the shoe 29 and thus move the pictures in the upper compartment the distance of one frame.

When the ascending pictures bear against the shoes 29 they will force the latter in 65 engagement with the locking devices or plates

23 and thus move the plates against the tension of the springs 27 to cut off the passage 30 at the front of the case or housing so as to lock the pictures in the upper compartment during the ascent of the pictures from the 70 lower compartment.

Secured to the top of the case 5 is a spring 31 the free end of which is bowed laterally and bears against the adjacent frame 10, there being a similar spring 31', preferably 75 secured to the upper face of the transverse partition 7 to assist in preventing accidental displacement of the frames in the compartment 8.

Pivotedly mounted in suitable recesses 32 80 in the guide bars 12 are kicking devices 33 the object of which is to lock the frames in the lower compartment 9 against accidental movement during the ascent of each picture.

One end of each kicking device 33 is bent 85 laterally within the lower compartment 9, as indicated at 34 while the opposite end thereof is extended to the upper surface of the adjacent sliding plate or locking device, as indicated at 35, so that the initial upward 90 movement of the ascending pictures from the lower compartment will bear against the upper end 35 of each kicking device and thus cause the opposite end thereof to bear against the remaining pictures in the lower 95 compartment 9 and lock the same against accidental displacement during the upward movement of the actuating device. It will thus be seen that by arranging the upper ends 35 of the kicking devices substantially 100 flush with the upper surfaces of the locking devices the frames 10 in the lower compartment are effectually locked against sliding movement until the ascending picture frame has completely entered the upper compartment 105 thereby preventing the picture frames from becoming wedged in the rear passage with consequent injury to and stoppage of the operating mechanism.

The bottom of the lower compartment 9 is 110 formed by an inclined plate 36 having one end thereof inclined or beveled at 37 so as to deflect the frames from the upper compartment downwardly and in position to be successively engaged by the lifting device.

In order to exhibit the photographs, stereoscopic views, or other pictures within the case or housing it is merely necessary to press the finger piece 18 against the action of the coiled spring 22 which causes the lifting 120 device 21 to engage the lower edge of the adjacent frame in the lower compartment 9. As soon as the pressure on the finger piece is released the spring 22 will elevate the lifting device together with the adjacent picture 125 carrying frame and deposit the latter in the upper compartment. The ascending picture carrying frame in its upward movement will first engage the upper end 35 of the kicking device so as to force the opposite end 130

34 thereof against the adjacent bank of picture carrying frames and thus prevent the weight of said frames from bearing against the ascending frame and impeding the upward movement thereof. A further movement of the ascending picture carrying frame will cause the latter to engage the flap or shoe 29 and force the plate or locking slide 23 to closed position so as to cut off the front 10 passage 30 and at the same time form a passage at the rear of the case or housing for the reception of the ascending picture.

When the slide or locking member 23 is moved forwardly to cut off the passage 30 15 the flap or shoe 29 will move the bank of picture carrying frames in the upper compartment the distance of one frame. As soon as the ascending picture frame clears the upper end of the shoe or flap 29 the tension of the 20 spring 27 will automatically move the locking member or slide 23 to close the passage at the rear of the case and open the passage 30 at the front of the case thus permitting an adjacent frame at the passage 30 to drop 25 by gravity into the lower compartment 9 so that the succeeding frame in the upper compartment may be exhibited at the display opening 6.

When the ascending picture frames enter 30 the upper compartment 8 they will successively bear against the spring 31, which latter forces said frames downwardly in engagement with the transverse partition.

It will thus be seen that by successively 35 depressing the finger piece 18 of the actuating device the pictures or picture carrying frames in the lower compartment may be consecutively transferred to the upper compartment so that the entire bank of photographs in the case or housing may be effectually displayed without the necessity of manually handling the same or exposing the pictures in any manner.

From the foregoing description it is 45 thought that the construction and operation of the device will be readily understood by those skilled in the art and further description thereof is deemed unnecessary.

Having thus described the invention what 50 I claim is:

1. A picture exhibitor including a case having a display opening and provided with superposed picture receiving compartments, there being a passage on one side of the case 55 and forming a source of communication between said compartments, means for transferring the pictures from one compartment to the other, means for automatically closing said passage during the ascent of the pictures 60 from one compartment to the other, and a kicking device disposed within one of the compartments and successively actuated by the ascending pictures for locking the remaining pictures in said compartment against accidental displacement.

2. A picture exhibitor including a case having a display opening and provided with picture receiving compartments, means for transferring the pictures from one compartment to another, and a kicking device operable by one of the ascending pictures in one compartment for locking the remaining pictures in said compartment against accidental displacement. 70

3. A picture exhibitor including a case 75 having a display opening and provided with a plurality of communicating picture receiving compartments, an actuating device for transferring the pictures from one compartment to another, means operable by the 80 ascending picture for cutting off communication between the compartments, and a kicking device disposed within one of the compartments and actuated by the ascending pictures for locking the remaining pictures in said compartment against accidental displacement. 85

4. A picture exhibitor including a case having a display opening and provided with communicating picture-receiving compartments, a yieldably supported actuating member, a lifting device pivotally mounted on the actuating member for successively transferring the pictures from one compartment to the other, and means for locking the 95 pictures in the upper compartment against accidental displacement during the ascent of the pictures in the lower compartment.

5. A picture exhibitor including a case having a display opening and provided with 100 communicating picture receiving compartments, an actuating member mounted for reciprocation in the case, a lifting member pivotally mounted on the actuating member and adapted to engage the pictures for successively transferring said pictures from one compartment to the other, and means extending in the path of movement of the ascending pictures for locking the pictures in one compartment against accidental displacement during the ascent of the pictures in the other compartment. 110

6. A picture exhibitor including a case having a display opening and provided with picture receiving compartments, means for 115 transferring the pictures from one compartment to the other, means for locking the pictures in one compartment during the ascent of the pictures in the other compartment, and a kicking device actuated by the 120 ascending pictures and adapted to bear against the pictures in one of said compartments.

7. A picture exhibitor including a case having a display opening and provided with 125 picture receiving compartments, an actuating device for successively transferring the pictures from the lower compartment to the upper compartment, a kicking device pivotally mounted in the lower compartment and 130

operable by the ascending pictures in said compartment, and means for locking the pictures in the upper compartment against accidental displacement during the ascent of 5 the pictures from the lower compartment.

8. A picture exhibitor including a case having a display opening and provided with a transverse partition forming superposed picture receiving compartments, there being 10 a passage on one side of the case and forming a source of communication between said compartments, means for transferring the pictures from one compartment to the other, and locking members slidably mounted on 15 the partition and actuated by the ascending pictures for automatically closing said passage during the ascent of the pictures from one compartment to the other.

9. A picture exhibitor including a case 20 having a display opening and provided with a transverse partition forming picture receiving compartments, said transverse partition being spaced from the adjacent walls of the case to form passages communicating 25 with both compartments, means for transferring the pictures from one compartment to the other, a locking device slidably mounted on the partition and normally closing one of the passages, said locking device being movable 30 able to close the opposite passage by engagement with the ascending pictures.

10. A picture exhibitor including a case having a display opening and provided with a transverse partition forming picture receiving compartments, there being passages 35 formed between the partition and the case, means for transferring the pictures from one compartment to another, a plate slidably mounted on the partition and normally closing one of the passages, and a pivoted section 40 bearing against the plate and movable in engagement with the plate to close the opposite passage by engagement with the ascending pictures.

45 11. A picture exhibitor including a case having a display opening and provided with a transverse partition forming picture receiving compartments, there being a passage formed on each side of the partition, means 50 for transferring the pictures from one compartment to the other, plates slidably mounted on the partition and normally closing one of the passages, shoes pivotally mounted on the partition and bearing against the adjacent ends of the plates, said shoes being movable 55 into engagement with the plates by the ascending pictures thereby to actuate the plates to cut off the opposite passage.

12. A picture exhibitor including a case 60 having a display opening and provided with a transverse partition forming picture receiving compartments, guides disposed within the case and spaced from the adjacent wall of the latter to form a rear compart-

ment, rods secured within the rear compartment, an arm slidably mounted on the rods, a lifting device carried by the arm and adapted to engage the pictures in one compartment for successively transferring said pictures to the adjacent compartment, and a 70 finger piece for actuating the arm.

13. A picture exhibitor including a case having a display opening and provided with picture receiving compartments, guides disposed within the casing and spaced from the 75 adjacent wall thereof to form a rear compartment, a spring pressed actuating member mounted for vertical movement within the rear compartment, a lifting device carried by the actuating member and adapted to engage 80 the pictures in one compartment for successively transferring said pictures to an adjacent compartment, and kicking devices pivotally mounted in the guides and adapted to bear against the pictures in one of said compartments.

14. A picture exhibitor including a case having a display opening and provided with picture receiving compartments, guides disposed within the case and spaced from the adjacent wall thereof to form a rear compartment, spaced rods disposed within the rear compartment, an arm slidably mounted on the rods, a plate pivotally mounted on the free end of the arm and adapted to engage 90 the pictures for successively transferring said pictures from one compartment to the other, a spring interposed between the arm and the case, and a finger piece for actuating 95 the arm.

15. A picture exhibitor including a case having a display opening and provided with picture receiving compartments, one of which is formed with an inclined bottom, spaced passages forming a source of communication between said compartments, means for successively transferring the pictures from one compartment to the other, a slide 105 for normally closing one of the passages, means operative by engagement with the ascending picture for moving the slide to automatically cut off the opposite passage, and a kicking device disposed within one of the compartments and actuated by the ascending pictures for locking the remaining pictures in said compartment against accidental displacement.

16. A picture exhibitor including a case having a display opening and provided with a transverse partition, defining communicating picture receiving compartments, there being a slot formed in one wall of the casing, spaced rods disposed within the casing, an arm slidably mounted on the latter and provided with a pivoted plate adapted to engage 120 the pictures in the lower compartment for successively transferring said pictures to the upper compartment, means for locking the 125

pictures in the upper compartment against accidental displacement during the ascent of the pictures in the lower compartment, a finger piece extending through the slot in the 5 casing for actuating the arm, and means for normally and yieldably holding the arm in elevated position.

In testimony that I claim the foregoing as my own, I have hereto affixed my signature in the presence of two witnesses.

ERNST CARL GUSTAV ROESLER.
